IVAR MEURLING, OF BROOKLYN, NEW YORK, ASSIGNOR TO EMPIRE DUPLEX GIN COMPANY, OF NEW YORK, N. Y., A CORPORATION OF ARIZONA.

DOFFER-MACHINE.

1,254,148.

Specification of Letters Patent. Patented Jan. 22, 1918.

Application filed May 22, 1915. Serial No. 29,715.

To all whom it may concern:

Be it known that I, IVAR MEURLING, a subject of the Crown of Sweden, residing at Brooklyn, Kings county, and State of New York, have invented certain new and useful Improvements in Doffer-Machines, of which the following is a specification, reference being had to the accompanying drawings, forming a part thereof.

10 My invention relates to apparatus for treating cotton and particularly to doffer machines or the like which are adapted to feed cotton from a bale opener into a lint flue or chamber containing air under pressure which leads it to a lapper.

15 One object of my invention is to provide an improved machine of the aforesaid character that shall be more simple and reliable than those hitherto known and subject to 20 less injury and wear.

25 Doffer machines have usually comprised a roll or rolls having paddles or vanes of leather or other flexible material extending radially outward, which were intended to feed the cotton into the lint flue and at the same time to seal the opening of the flue. Machines of this kind are objectionable because they tend to wear rapidly and to work 30 badly on account of the leather losing its flexibility and permitting the air in the flue to blow back the cotton. The usual apparatus for conveying the cotton to the doffer machine is so constructed, having spikes or 35 nails for carrying the cotton, that there is danger of fire by striking a spark and igniting the cotton. A fire once started in the flue would travel with great rapidity and do a large amount of damage.

40 One object of my invention is to overcome this risk and in fact my doffer structure is so arranged that if the cotton in the hopper should be ignited the fire will be extinguished by the doffer rolls before it is delivered to the flue.

45 Other objects and advantages of my invention will be set forth hereinafter, and in order that my invention may be thoroughly understood, I will now proceed to describe the same in the following specification and then point out the novel features thereof in 50 appended claims.

Referring to the drawings:

Figure 1 is a front view of a doffer ma-

chine arranged and constructed in accordance with my invention.

55 A partially sectional front elevation of one end of the doffer machine showing the rolls, is illustrated in Fig. 2.

Fig. 3 is a sectional end elevation, taken 60 on the line 3—3 of Fig. 2.

As shown in Fig. 1, the machine comprises a body built up of side frames 10 and cross-rolls or stays 11, a conveyer platform 12 adapted to receive the cotton, a hopper 13 to which the cotton is transferred by the conveyer, rolls 14, 15 and 16, and driving mechanism therefor.

65 The conveyer 12 may be of any suitable type, an endless belt rack 17 extending as shown in the drawings around a pair of pulleys or sheaves 18 and 19. The arrangement of parts is such that the top section of the conveyer constitutes a receiving platform onto which cotton may be thrown. The pulley 19 is mounted on bearings carried by 70 adjustable brackets 20 so that the conveyer may be maintained in any desired tension.

75 Adjacent to the opposite end of the conveyer the side frames 10 extend upwardly and are provided with a cover-plate 21 to 80 constitute a receiving hopper, to which the cotton is delivered from the conveyer. Directly under the hopper near the bottom of the body of the machine is a chamber 22 which is adapted to form a part of a lint 85 flue, sections 23 and 24 of the flue being shown as fitted onto flanges 25 and 26 with which the end frames of the machine are provided.

80 The flue, including the chamber 22, is closed except where it opens into the hopper, and into this opening, which is indicated at 27, the doffer rolls 15 and 16 extend.

85 The roll 16 is secured to a shaft 28 which 90 has a sprocket wheel 29 and a bevel gear 30, and is rotatively mounted in the frame. The shaft 31 which is substantially parallel with the shaft 28 is also rotatively mounted in the frame. It has a sprocket wheel 32 100 near one end and a gear wheel 33 near the opposite end. Suspended from the shaft 31 are a pair of brackets 34 which form bearings for a shaft 36 which is parallel with the shaft 31 and has secured to it a doffer roll 105 15. When the doffer rolls 15 and 16 are to-

gether as shown in Fig. 2 of the drawings, the shaft 36 is directly below the shaft 31 and the shafts 28 and 36 are substantially in the same horizontal plane. These relative positions are however, not essential.

In order to press the rolls 15 and 16 together, a weight 37 is suspended between the brackets 34, its points of attachment to the brackets being materially offset from the vertical plane of the shafts and consequently it tends to swing the brackets about the shaft 31 as an axis and press the roll 15 against the roll 16.

The shaft 36 is provided with a gear wheel 38 which meshes with the gear wheel 33, an operative connection being thus formed from the shaft 31 to the roll 15. The arrangement of parts is obviously such as not to interfere with the swinging of the roll 15 since the pivotal axis for the suspension brackets 34 is the center of the shaft 31. A pair of adjustable brackets 40 are pivotally mounted on sleeve projections 41 with which the brackets 34 are provided and support a shaft 42 to which the roll 14 is secured. The frames 10 are provided with slots 43 and the ends of the brackets 40 are clamped in any suitable position to which they are adjusted, by bolts 44 which extend through the slot 43, the adjustment of the brackets being of course limited by the length of the slot.

This constitutes a convenient means for adjusting the position of the roll 14 which is for the purpose of pushing the cotton downwardly, as it leaves the conveyer 12, onto the doffer rolls 15 and 16.

The roll 14 may be rotated by any suitable driving means; for example, it may be connected to the shaft 31 by a gear 14^a meshing with gear 33, or connected in some other way to a driven member.

45 represents the main driving pulley of the machine although the machine may be driven in any suitable manner. The pulley 45 is mounted on the shaft 46 supported in suitable bearings 47 and having a bevel pinion 48 at one end which meshes with the bevel gear 30. The shaft 28 is thus driven and a driving connection is established from this shaft to the shaft 31, and to a shaft 49 on which the pulley 18 is mounted, by means of a sprocket chain 50 which meshes with the sprocket wheels 29 and 32, and a sprocket wheel 51 mounted on the shaft 49. An idler pulley 52, mounted on an adjustable bracket 53 is provided for the purpose of adjusting the tension of the chain.

The hopper 13 is provided with an apron 54 which diverts the cotton onto the doffer 55 rolls.

Each of the doffer rolls is provided with a shoe 55 which extends longitudinally of the roll and engages its outer surface adjacent to the edges of the opening 27 into the chamber 22. These shoes are mounted on yielding

strips 56 which are bolted to the top of the chamber, thereby sealing the opening from the chamber into the hopper and preventing the loss of air pressure in the flue or the blowing out of the cotton which is intended to be delivered to the flue.

The shoes 55 are pressed into engagement with the respective doffer rolls by means of spring-pressed levers 57. As indicated in Figs. 2 and 3, each of the doffer rolls is preferably provided with grooves 60 in its outer surface in order to avoid the clogging of the machine as hereinafter explained.

The operation of the apparatus is as follows: Assuming that the shaft 46 is operated so that the shafts 28 and 31 and 49 are driven in a clockwise direction, as shown in Fig. 2, the shaft 36 will obviously be driven in a counter-clockwise direction so that the doffer rolls 15 and 16 cooperate without material wear or friction. When the machine is thus operated, if cotton is thrown onto the conveyer platform 12, it will be carried into the hopper 13, the roll 14 serving to push it downwardly between the rolls 15 and 16. These rolls will act as feed rolls and will carry the cotton between them into the chamber 22, particularly on account of their grooved or otherwise roughened surfaces which prevent slipping. As this chamber is a part of the lint flue, the cotton will be conveyed away by the usual current of air therein.

As the cotton is squeezed between the rolls, due to the action of the weight 37, the roll 15 will swing outwardly to a greater or less extent to permit the cotton to pass through, but I have found that no material space will be open and no loss of pressure in the lint flue or blowing back of the lint will occur.

Since the cotton is squeezed between the rolls as it is fed into the flue, fire or flame started in the hopper will not be transferred to the flue but will be smothered as the cotton passes through the rolls.

Structural variations may be effected without departing from the spirit and scope of my invention, and I intend that only such limitations be imposed as are indicated in the appended claims.

What I claim is:

1. A doffer machine comprising a conveyer adapted to be supplied with cotton, a hopper into which the conveyer discharges, a lint flue adapted to have air pressure therein and opening into the hopper, and a pair of cylindrical doffer rolls disposed in the opening and adapted to rotate with their peripheries in variable proximity to feed cotton into the flue, shoes engaging the non-adjacent portions of the doffer roll surfaces, springs exerting pressure upon the shoes, yielding means for connecting the shoes to the adjacent edges of the opening into the flue, a pivotal bracket supporting one of

the doffer rolls, an operative driving connection for the rolls arranged to permit the free pivotal movement of said supporting bracket and its roll, and a weight tending to hold the doffer rolls together.

2. A doffer machine comprising a conveyer adapted to be supplied with cotton, a hopper into which the conveyer discharges, a lint flue adapted to have air pressure therein and opening into the hopper, and a pair of cylindrical doffer rolls disposed in the opening and adapted to rotate with their peripheries in variable proximity to feed cotton into the flue, shoes engaging the non-adjacent portions of the doffer roll surfaces, springs exerting pressure upon the shoes, yielding means for connecting the shoes to the adjacent edges of the opening into the flue, a pivotal bracket supporting one of the doffer rolls, an operative driving connection for the rolls arranged to permit the free pivotal movement of said supporting bracket and its roll, a weight tending to hold the doffer rolls together; and a roller mounted in the hopper and adapted to push the cotton downwardly onto the doffer rolls as it is received from the conveyer.

3. A doffer machine comprising a conveyer adapted to be supplied with cotton, a hopper into which the conveyer discharges, said hopper being open at the top, a lint flue below the hopper, adapted to have air pressure therein, a pair of cylindrical doffer rolls disposed between the hopper and the lint flue, the ends of said rollers forming

airtight closures between the hopper and the flue, yieldable means for forming airtight closures between outer surfaces of the rollers, the hopper and the flue, means for rotating said rollers in any of their positions in opposite directions to feed cotton into the flue, means for pressing said rollers against each other or against the cotton between them and a transversely movable support for one of said rollers.

4. A doffer machine comprising a conveyer adapted to be supplied with cotton, a hopper into which the conveyer discharges, said hopper being open at the top, a lint flue below the hopper adapted to have air pressure therein, a pair of cylindrical doffer rolls disposed between the hopper and the lint flue, the ends of said rollers forming airtight closures between the hopper and the flue, yieldable means for forming airtight closures between outer surfaces of the rollers, the hopper and the flue, a pivoted transversely movable support for one of said rollers, means for pressing said rollers against each other or against the cotton between them, and driving gearing for rotating said rollers in opposite directions to feed cotton into the flue, the gearing for one of said rollers comprising a gear having its axis in alinement with the pivot of said movable support.

In witness whereof, I have hereunto set my hand this 20th day of May, 1915.

IVAR MEURLING.
